APPARATUS FOR WEATHERPROOFING
COMPOSITION BOARD

Robert S. Maclean and Charles W. Pollard,
Michigan City, Ind., assignors to Mastic As-
phalt Corporation, Michigan City, Ind., a cor-
poration of Indiana

Application November 17, 1934, Serial No. 753,472

18-Claims. (CL. 91—43)

Our invention relates to an apparatus for constructing building material and relates more specifically to apparatus for constructing weatherproofed building material.

5 The building material to which we refer is of the general type shown and described in the co-pending application of Robert S. Maclean filed November 16, 1931, and bearing Serial No. 575,449.

10 The principal object of the present invention is to provide an apparatus by the use of which it is possible to take insulated board or composition board of any and all kinds and by a continuous process apply the weatherproof coating thereto.

15 A further object of the invention is to provide apparatus of this type capable of weatherproofing composition board or similar substance of any thickness, and also capable of applying a weatherproof coating of any desired thickness.

20 A further object of the present invention is to provide in an apparatus of the class described improved conveying means for carrying the material through the machine.

25 A further object is to provide improved weatherproof coating means capable of applying a layer of a desired thickness to a sheet of composition board.

30 A further object is to provide improved weatherproofing material reservoirs and treating means in association with an apparatus of the class described.

35 A further object is to provide an improved apparatus for manufacturing a weatherproofed composition board that will simulate brick.

40 A further object of our invention is to provide a novel product in the form of a building material unit.

45 A further object of the invention is to provide a product of this type capable of being applied to a building to cover the entire exterior surface thereof.

50 A further object of the invention is to provide a novel building material unit so constructed that in applying the same to a building practically all of the material can be used in one place or another, thus entirely eliminating any waste in the application thereof.

55 A great many other advantages and features will be found in the invention as shown and described; some of the features of the apparatus reside in the specific construction of the heating means for the conveyor, the arrangement and means for heating and applying the weatherproofing material, the means for applying the weatherproofing grit, means for removing excess

grit and the means for feeding portions of the excess grit to positions at which they are utilized.

The above and other advantages and features will be more clearly understood in connection with the following description of one specific embodiment of our invention wherein reference is had to the accompanying thirteen sheets of drawings upon which such an apparatus has been illustrated, together with the novel product that is manufactured thereby.

5

10 In the drawings:

Fig. 1 is a plan elevational view of a sheet of ordinary untreated composition board such as celotex, of a size which it is desired to treat;

Fig. 2 is a similar view of the same sheet which has been weatherproofed in accordance with our invention and has been marked or imprinted to simulate brick work;

Fig. 3 is an enlarged cross-sectional view of the weatherproofed material taken generally on 20 the line 3—3 of Fig. 2;

Fig. 4 is a side elevational view of the complete apparatus;

Fig. 5 is a longitudinal sectional view of the forward portion of the apparatus showing the 25 loading platform and the initial conveyors;

Fig. 6 is a plan view of the same portion of the apparatus;

Fig. 7 is a side elevational view of that unit of the apparatus at which the weatherproofing 30 material is applied;

Fig. 8 is a similar elevational view taken from the opposite side of the machine;

Fig. 9 is a longitudinal section of the same portion of the machine taken generally through 35 the central portion thereof;

Fig. 10 is a plan view of the weatherproofing unit;

Fig. 11 is a longitudinal sectional view of a portion of the machine beyond the weather- 40 proofing applying section taken generally through the center of the machine;

Fig. 12 is a plan view of the portion of the apparatus shown in Fig. 11.

Fig. 13 is a central longitudinal section through 45 a continuation of the machine illustrating the dust-sucking apparatus;

Fig. 14 is a vertical sectional view taken generally on the line 14—14 of Fig. 13;

Fig. 15 is a central sectional view of the ap- 50 paratus extending beyond that portion thereof shown in Fig. 13;

Fig. 16 is a vertical sectional view taken on the line 16—16 of Fig. 15.

The invention will be described first with par- 55

ticular reference to the novel building material which is produced thereby and in order to explain the same, reference may be had to Figs. 1 to 3, inclusive. A sheet 10 of rigid composition board of desired size and shape and provided with off-set edge portions 11 and 12 and undercut edge portions 13 and 14, is adapted to be fed through the machine. When processed by the machine, one face of the sheet or panel 10 is coated with a layer of asphalt A in which grit G of crushed brick or other suitable substance is partially imbedded to provide a waterproof surface. Grooves 15 are pressed in said coated face, with the grits G' at the grooved portions completely imbedded and hidden. The panel is thus provided with a waterproof face having a design configuration simulating brickwork, or the like.

The machine generally may have a loading platform 25, a primary conveyor unit 26, an asphalt or weatherproofing unit 27, a grit supply and applying unit 28, an intermediate conveyor unit 29, an excess grit removing unit 30, a timed unit feed mechanism 32 and an imprinting unit 31, and an unloading platform 34.

The entire apparatus may be mounted upon parallel angle-iron frame members 35 which are supported throughout their entire length by a plurality of angle leg members 36. Adjacent the loading platform 25 a plurality of sprocket wheels 37 are arranged to be mounted upon a cross-shaft 38 journalled in suitable bearings 39 mounted upon the parallel frame members 35. In the embodiment of our invention shown in the drawings, we provide four of the sprocket wheels 37 equally spaced between the frame members 35. As previously mentioned, the material upon which it is desired to operate is 30 inches wide and accordingly the apparatus is of a sufficient width so that material of this size may be moved forwardly between side guide angles 41 by suitable conveyor chains 40 mounted on the sprockets 37.

The side guide angles 41 are supported upon uprights 42 extending from the frame members 35. Additional support members are provided between the sprockets and comprise the T-shaped members 43 which are supported upon cross-members 44. The cross-members 44 are fastened to the uprights 42. The conveyor chains 40, together with the side guide angles 41 and the T-shaped members 43 extend forward to the weatherproofing applying unit 27, the conveyor chains 40 being geared to a group of sprocket wheels 45 similar to sprockets 37. These sprocket wheels are also mounted upon a cross-shaft 46 journalled in suitable bearings 47 rigidly mounted upon the side frame members 35. The conveyor chains 43 are supported intermediate the sprocket wheels 37 and 45 by plate members 48 supported by the upright frame members 42. The shaft 46 extends beyond its bearing on one side and has an enlarged sprocket wheel 49 keyed thereto which is driven by means of a chain 50 from a sprocket wheel 51 mounted upon cross-shaft 52 of the pulling rollers adjacent the weatherproofing unit 27. Sprocket wheels 52a, 52b and chains 52c and 52d, drive sprocket wheels 101f and 78a on the grit box roller 101 and on the conveyor sprocket shaft 78, later to be described.

Referring now more specifically to Figs. 7 to 10 inclusive, a pair of pulling rollers 53 and 54 are provided, mounted in a pair of brackets 55 which are rigidly secured to the side frame mem-

bers 35. The rollers 53 and 54 are so positioned and adjustably mounted that the same may be moved to a proper position and separated to the desired width of the material which is to pass therebetween.

Means for actuating the upper roller 54 may comprise a lever 56 secured to a cross-shaft 57 that is journalled in a suitable bearing 58 of the brackets 55. This shaft may carry an eccentric 59 that has an adjustable member 60 secured thereto and bearing against a compression spring 61. The compression spring 61 is mounted upon the bearing support for roller 54 and thus by spring pressure the roller is yieldingly held downwardly against the material passing through the machine.

The rollers 53 and 54 are adapted to be driven in a direction to pull the material through the machine by a pair of intermeshing gears 62 and 63 mounted upon the roller shafts 52 and 54 respectively.

The rollers 53 and 54 serve to pull the material forward under a spout 70 extending from an asphalt storage tank 71. The flow of melted asphalt from this storage tank is controlled by a valve 72 attached to one wall thereof, and the valve is operated through a link connection 73 with a hand lever 74 positioned on the left side of the machine. Directly below the spout 70 and above the material passing through the machine, we provide a horizontally positioned U-shaped member or grate 75 which has a back wall 76 extending parallel to rollers 53 and 54 to prevent the flow of asphalt on the panels being coated toward the pulling rollers 53 and 54. This grate 75 is supported at its forward end upon a pair of post members 76 secured to the frame members 35 and at its rear end by a pair of angle plates 77 secured to the brackets 55. The material is supported below the spout and to a point adjacent a conveyor chain 78 by T-shaped members 79 similar to the members 43 previously described. The members 79 are supported upon one end by an angle member 80 secured to the brackets 55 and at their opposite end by a similar angle member 81 secured to a pair of uprights 82 that are fastened to the side frame members 35. An asphalt overflow tank 83 is positioned below the spout 70 and the grate 75 and is sufficiently wide so that asphalt flowing over the edges of the material will drop into the same. This tank is securely fastened to the underside of the side frame members 35.

The overflow tank 83 has an outlet conduit 84 connected thereto from which a return pipe 85 extends to the upper end of the asphalt tank 71 so that all of the asphalt which overflows can be returned to the storage tank.

An asphalt spreading device 86 is positioned slightly forward from the spout 70 and comprises a horizontal pipe member mounted upon suitable upright pipe connections 87 that are connected to a similar cross-pipe 88 at a point below the material path. The cross-pipe 88 is pivotally mounted in a pair of brackets 89 positioned at the sides of the machine so that by moving the lever 90 connected with one side thereof the height of the asphalt spreader 86 can be adjusted as desired. A similar spreading roller 90' is arranged to be positioned slightly in advance of the roller 86 and may also extend across the machine.

The spreader 90' is eccentrically mounted in suitable bearings 91 and 92 having at one end a drum 93 upon which indicia is marked so that

the height of the spreader from the material may be determined. The means for moving the spreader member comprise a hand lever 94 that is keyed to the shaft upon which the spreader is mounted. The roller 95 may be positioned directly below the spreader 90 so that the material passing below the spreader will be uniformly supported. It will be noted (see Fig. 9) that the T-shaped supports 18 are cut off adjacent the roller 95 and supported upon cross-angle members 96 and 97.

After the material passes beneath the spreading roller 90, it passes below a grit box 100 within which a quantity of grit is adapted to be fed to the top of the material by the usual toothed roller 101 which is rotated to deliver the grit from the bottom of the grit box. A sliding gate 102, which is operated by a hand wheel 103 through suitable gears 104 and racks 105, controls the thickness of the layer of grit which is allowed to drop upon the hot asphalt upon the material.

A hand lever 101a, positioned upon the left side of the machine, is pivotally mounted upon a bracket 101b and connected through a rod 101c with a clutch operating member 101d to engage or disengage the drive for the roller 101.

The grit box is supported by a plurality of uprights 106 extending upwardly from the side frame members 35. Means for providing a more uniform coating of grit and one in which the dust and smaller grit are more or less eliminated from the coating, are provided in the form of a blower unit 107 secured to the machine adjacent the grit box 100.

The blower 107 has a flattened, narrow-mouthed funnel 108 which extends across the width of the machine and which is connected to an air conduit 109 which extends upwardly to a source of air pressure. A valve 110 is provided in the conduit 109 for controlling the amount of air that is used. A pair of straps 111 and 112, which are attached to the grit box 100, rigidly support the blower in position.

The material which is passed through the weatherproofing unit hereinbefore described, again passes upon conveyor chains 78, which are mounted upon suitable sprockets 113. The sprockets are keyed to a shaft 114 that is journaled in suitable bearings 115 upon the frame members 35, similar to the previously described sprocket assemblies. The side guides from this point forward in the machine are in the form of square tubular members 116 which are mounted at their forward end upon the angle members 81 and are secured thereto by strap members 117. These tubular members are adapted to be heated by steam or other suitable heating material for a purpose which will be presently described.

In connection with the weatherproof applying unit it is desired to heat the several devices which operate upon the material. Accordingly, a supply of gas or other combustible material is provided, being received through a gas supply pipe 118 which extends upwardly and through a suitable burner mechanism 119 which is adapted to enter the spreading roller 90. A lead 120 may extend therefrom and pass through a burner and carbureting mechanism 121 into a pipe 122 positioned in the lower end of the asphalt overflow tank 83. The pipe 122 may extend transversely of the tank 83 and have a cross-member 123 and a return pipe 124 so that substantially all of the floor area of the overflow tank is kept at a high

degree of heat to keep any asphalt which may flow over the edges of the material into the tank in liquid form. A supply of steam is utilized to heat the primary spreading unit 86 and may be fed into the lower pipe 88 through a steam conduit 125 which is connected to a supply pipe 126. The pipe 126 may have an extension 127 which connects with the lower roller 95 of the second spreader unit. The steam supply pipe 126 may also have an extension 128 which is connected to one tubular side member 116 and also has a suitable cross-connection 129 to the tubular side member 116 upon the opposite side of the machine.

After the material has been weatherproofed upon one face by the mechanism which has been described, it passes forward upon the chain conveyors 78. During its progress upon the chain conveyors 78, the material passes beneath a plurality of transverse pressure rollers 140. These pressure rollers which are driven to pull the material forward in a manner which will be further described, are spaced at intervals upon the frame members 35 and are supported in bracket members 141. The roller pillow blocks 142 are mounted in upright slides 143 in the bracket members and have a screw member 144 secured thereto which extends upwardly through a cover plate 145. A compression spring 146 is mounted between the cover plate 145 and a screw-threaded washer member 147 is mounted upon the member 144. The washer can be moved upwardly and downwardly upon the member 144, thus increasing or decreasing the compression upon the spring 146 which in turn increases or decreases the pressure of the rollers 140 upon the material. T-shaped members 150 similar to those previously described support the material between the conveyor chains, and plate members 151 support the upper side of the conveyor chains during the forward movement of the material.

In order to avoid an uneven forward progress of the material, due to asphalt clinging to the edges thereof and sticking to the side guide members, the side guide members throughout the machine from the asphalt applicator forward may be heated similarly to the members 116. Accordingly the side guide members 152 may be tubular in shape and be connected by suitable piping 153 at the rollers 140 with the tubular members 116 so that at all times a heated side guide wall is provided except for the short interval at the roller bearing brackets 141.

The T members 151 and the supporting plates 150 may be supported upon the frames 35 by angle members 42 and suitable cross-members 44.

The rollers 140 may be driven in a direction to move the material forward by a suitable drive. A chain 154 is trained about a pair of sprocket wheels 155 and 156 and in this manner the first roller 140 is driven. A chain 157 extending from the second roller to the third furnishes a drive for the second roller 140. A third chain 158 extends from the third roller forward to the excess grit removing unit where the drive therefor will be further explained.

This drive is furnished by a sprocket wheel 159, (see Fig. 14) which is fastened to the end of an upper roller shaft 160. A pair of gears 161 and 162 are mounted upon shaft 160 and a cross-shaft 163 respectively. A sprocket wheel 164 secured to shaft 163 is arranged to be driven from an enlarged sprocket wheel 165 keyed to shaft 162 by means of a chain 166.

The roller shaft 160 has a pressure roller 167

mounted thereon which extends transversely across the machine and which is mounted in a pair of bracket assemblies 168 similar to bracket assemblies 141, previously described. A second pressure roller 169 is mounted slightly spaced therefrom in a similar bracket assembly 170. Disposed between the two rollers is a sucker unit 171 which comprises generally a conduit 172 having a flattened transverse nozzle 173, a valve 174 and a source of suction 175. The source of suction may comprise a blower unit mounted upon a dust bin 176 into the lower end of which the conduit 172 extends. This apparatus may generally draw from the face of the material all of the excess grit which are not adhered to the asphalt, together with all the dust and other sediment thereon. The same is arranged to be drawn upwardly into the bin 176 where the suction unit 175 draws off the dust and lighter sediment, leaving as a deposit in the lower end of the box all of the larger grit so that the same may be utilized at another time.

An extension 177 extends from the previously described steam pipes and connects through suitable fittings with the two side guide members 178. A second sprocket wheel 179 is secured to shaft 163 and through a chain 180 is arranged to drive a sprocket wheel 181 mounted upon a cross-shaft 182. The cross-shaft 182 has a plurality of sprocket wheels 183 mounted thereon which have the conveyor chains 184 geared thereto.

The machine as thus far described is capable of taking composition board sheets into the same at one end, coating the sheet upon one face with a layer of asphalt of any desired thickness, placing a quantity of grit upon the asphalt while in a hot state, thus allowing the same to be embedded therein and adhered thereto and then carrying the sheet in this manner forward, pressing the grit into the asphalt at different intervals during the travel of the sheet, and finally removing excess grit, sand, dust and other sediment from the surface thereof so that as the material leaves the excess grit remover the same is complete, capable of being removed from the conveyor and used. However, it is frequently desired to impress different designs upon the material and accordingly the material continues from this point between a pair of rollers 200 and 201, (see Fig. 15).

The rollers 200 and 201 are pressure rollers which are adapted to be held into resilient engagement with the material passing through the apparatus by an assembly including a compression spring 61, eccentric bearing member 69 and lever 66 similar to that previously described.

The rollers are mounted in suitable brackets 210 upon opposite sides of the machine.

The T-members 180 may extend to and be supported upon a cross-angle 211 and the chain supporting plates 151 may be supported upon a similar cross-angle 42 mounted upon uprights 44. The side guide members 178 may be suitably secured to the cross-members 42 and extend to the brackets 210 at which point a feed pipe 212 may extend upwardly therefrom to the further side guide members 255.

The lower roller 201 may be provided with a doctor plate 213 which is fastened to a cross-angle 214 mounted between the brackets 210. The purpose of this doctor plate is to scrape off any asphalt which may have adhered to the lower side of the material and have become stuck upon the roller 201. As a further means for keeping the roller 201 smooth and polished at

all times, a flexible buffer member 215 may be positioned bearing against the opposite side of the roller. The buffer 215 may be mounted on a cross-bar 216 that is resiliently positioned and held by a pair of bolts 217 secured to the brackets 210.

From the pressure rollers 200 and 201, the material moves to a point at which it is manually transferred to imprinting unit 31 (Fig. 4) by means of which the grooves 15 are impressed upon the coated face of panel 10. This unit operates in timed relation with the device heretofore described by means of a chain 320 connected with the previously described device by running over gear 325. The entire device is preferably driven from a suitable motor which may have a drive shaft 218 upon which pinion 211 is mounted. Pinion 211 may mesh with gear wheel 272 which in turn operates through suitable gearing including gear 275 meshing with gear 285 associated with the imprinting means and having a driving connection with the gear of unit 31 over which chain 320 is trained.

What we claim is:

1. Apparatus for constructing a weatherproof building covering unit, comprising a longitudinal base, a plurality of conveyors mounted on said base, heated guides along the sides of said base, an asphalt supply and discharge positioned above said base for allowing a flow of hot asphalt to a composition board upon said conveyors, rollers above and below the board for smoothing out and regulating the thickness of said asphalt, a grit supply, means for feeding grit to the upper side of said board situated adjacent said asphalt supply and conveyor means for moving said board away from the asphalt and grit applying positions.

2. Apparatus for constructing a weatherproof building covering unit, comprising a longitudinal base, a plurality of conveyors mounted on said base, heated guides along the sides of said base, an asphalt supply and discharge positioned above said base for allowing a flow of hot asphalt to a composition board upon said conveyors, means for controlling the same, rollers above and below the board for smoothing out and regulating the thickness of said asphalt, a grit supply, means for feeding grit to the upper side of said board situated adjacent said asphalt supply and conveyor means for moving said board away from the asphalt and grit applying positions.

3. Apparatus for constructing a weatherproof building covering unit, comprising a longitudinal base, a plurality of conveyors mounted on said base, heated guides along the sides of said base, an asphalt supply and discharge positioned above said base for allowing a flow of hot asphalt to a composition board upon said conveyors, means for controlling the same, rollers above and below the board for smoothing out and regulating the thickness of said asphalt, a grit supply, means for feeding grit to the upper side of said board situated adjacent said asphalt supply, means for controlling the same, and conveyor means for moving said board away from the asphalt and grit applying positions.

4. Apparatus for constructing a weatherproof building covering unit, comprising a longitudinal base, a plurality of conveyors mounted on said base, heated guides along the sides of said base, an asphalt supply and discharge positioned above said base for allowing a flow of hot asphalt to a composition board upon said conveyors, means

- for controlling the same, rollers above and below the board for smoothing out and regulating the thickness of said asphalt, an asphalt overflow tank positioned below the asphalt discharge, a 5 grit supply, means for feeding grit to the upper side of said board situated adjacent said asphalt supply, means for controlling the same, and conveyor means for moving said board away from the asphalt and grit applying positions.
- 10 5. Apparatus for constructing a weatherproof building covering unit, comprising a longitudinal base, a plurality of conveyors mounted on said base, steam heated guides along the sides of said base, an asphalt supply and discharge positioned above said base for allowing a flow of hot asphalt to a composition board upon said conveyors, heated rollers above and below the board for smoothing out and regulating the thickness of said asphalt, a grit supply, means for feeding grit to the upper side of said board situated adjacent 15 said asphalt supply conveyor means for moving said board away from the asphalt and grit applying positions, and suction means for removing excess loose grit from said unit.
- 20 6. Apparatus for constructing a weatherproof building covering unit, comprising a longitudinal base, a plurality of conveyors mounted on said base, heated guides along the sides of said base, an asphalt supply and discharge positioned above said base for allowing a flow of hot asphalt to a composition board upon said conveyors, an overflow tank therebeneath, means for controlling the asphalt flow, heated rollers above and below the board for smoothing out and regulating the thickness 25 of said asphalt, a grit supply, means for feeding grit to the upper side of said board situated adjacent said asphalt supply, conveyor means for moving said board away from the asphalt and grit applying positions, pressure rollers associated with said conveyor means, an excess grit removing mechanism and means connected therewith for separating useful grit from sand, dust and other sediment removed therefrom.
- 30 7. Coating apparatus comprising an interrupted support along which a rigid blank is propelled, means above said support for flowing hot plastic on one face of said blank, spaced transverse members at said support interruption between which said coated blank is fed while on said support to level the plastic on said board, and means for heating at least the member engaging the uncoated face of said blank.
- 35 8. An apparatus for coating one face of a blank comprising a frame mounting means for conveying a blank, means for applying thermoplastic material to the upper face of said blank, a support pivoted to said frame in vertically spaced relation to the path of movement of said blank and means carried by said support for heating and spreading said thermoplastic material on said blank in uniform predetermined thickness, said last named means being vertically adjustable relative to said blank by pivoting of said support.
- 40 9. An apparatus for coating one face of a blank comprising a frame mounting means for conveying a coated blank, means for applying thermoplastic material to the upper face of said blank, and heated means for spreading said material uniformly in predetermined thickness on said blank including a support shiftable about a trans-
- 45 verse axis vertically spaced from the path of movement of said blank.
- 50 10. Coating apparatus comprising a conveyor for a rigid blank, means above said conveyor for flowing hot plastic on said blank, heated means in predetermined relation to said conveyor for re-heating and uniformly distributing said plastic on said blank, means adjacent said heated means for covering said reheated plastic with granular material, and heated means for guiding the movement of said coated blank on said conveyor. 55
- 55 11. Coating apparatus comprising a conveyor for a rigid blank, means for coating one face of said blank with thermoplastic material, and steam conduits parallel to said conveyor and engaged by the edges of said blank to guide the movement of said coated blank on said conveyor. 60
- 60 12. Apparatus for weatherproofing sheet building material comprising means for applying hot thermoplastic coating to one face of the material, means for smoothing out said coating, means for applying a layer of grit to said coating, suction means for removing loose excess grit thereon, a conveyor, and a heated guide for said material extending longitudinally of said conveyor and intermediate said coating and suction means for edge contact with the coated material. 65
- 65 13. Apparatus for weatherproofing rigid blanks comprising a conveyor, means for flowing thermoplastic coating on one face of said blank, and elongated heated members engaging opposite edges of said coated blank to guide said blank on said conveyor. 70
- 70 14. An apparatus for coating the upper face of a blank, comprising means for carrying a blank in horizontal position, including rotating feed rolls, means spaced from said rolls for flowing hot thermoplastic coating on the upper face of said blank, means for spreading said coating over said blank, and means above the blank and between said coating means and rolls for retaining excess coating piled up on said blanks by said spreading means spaced from said rolls. 75
- 75 15. An apparatus for coating one face of a rigid blank, comprising interrupted horizontal guide means for carrying a blank in horizontal position, means for flowing hot thermoplastic coating on the upper face of said blank, heated means for spreading said coating on said blank, and a pair of members at said interruption spaced in predetermined relation above and below said blank to control the thickness of the coating, the member engaging the uncoated face of the blank being heated. 80
- 80 16. The apparatus of claim 15, wherein said spreading means is carried by supporting means pivoted in vertically spaced relation below the blank. 85
- 85 17. The apparatus of claim 15, wherein said spreading means comprises vertically spaced rigidly interconnected steam pipes, one of said pipes below said blank being journaled in said blank carrying means. 90
- 90 18. The apparatus of claim 15, wherein the member engaging the coated face of the blank is eccentrically journaled in a support at its ends, and means for locking said member in predetermined position against rotation. 95

DISCLAIMER

2,163,757.—Robert S. Maclean and Charles W. Pollard, Michigan City, Ind. APPARATUS FOR WEATHERPROOFING COMPOSITION BOARD. Patent dated June 27, 1939. Disclaimer filed May 13, 1942, by the assignee, Mastic Asphalt Corporation.

Hereby enters this disclaimer to claims 1, 5, 9, 10, 12, and 13 of said Letters Patent.

[Official Gazette June 16, 1942.]

- for controlling the same, rollers above and below the board for smoothing out and regulating the thickness of said asphalt, an asphalt overflow tank positioned below the asphalt discharge, a 5 grit supply, means for feeding grit to the upper side of said board situated adjacent said asphalt supply, means for controlling the same, and conveyor means for moving said board away from the asphalt and grit applying positions.
- 10 5. Apparatus for constructing a weatherproof building covering unit, comprising a longitudinal base, a plurality of conveyors mounted on said base, steam heated guides along the sides of said base, an asphalt supply and discharge positioned above said base for allowing a flow of hot asphalt to a composition board upon said conveyors, heated rollers above and below the board for smoothing out and regulating the thickness of said asphalt, a grit supply, means for feeding grit to the upper side of said board situated adjacent 15 said asphalt supply conveyor means for moving said board away from the asphalt and grit applying positions, and suction means for removing excess loose grit from said unit.
- 20 6. Apparatus for constructing a weatherproof building covering unit, comprising a longitudinal base, a plurality of conveyors mounted on said base, heated guides along the sides of said base, an asphalt supply and discharge positioned above said base for allowing a flow of hot asphalt to a composition board upon said conveyors, an overflow tank therebeneath, means for controlling the asphalt flow, heated rollers above and below the board for smoothing out and regulating the thickness 25 of said asphalt, a grit supply, means for feeding grit to the upper side of said board situated adjacent said asphalt supply, conveyor means for moving said board away from the asphalt and grit applying positions, pressure rollers associated with said conveyor means, an excess grit removing mechanism and means connected therewith for separating useful grit from sand, dust and other sediment removed therefrom.
- 30 7. Coating apparatus comprising an interrupted support along which a rigid blank is propelled, means above said support for flowing hot plastic on one face of said blank, spaced transverse members at said support interruption between which said coated blank is fed while on said support to level the plastic on said board, and means for heating at least the member engaging the uncoated face of said blank.
- 35 8. An apparatus for coating one face of a blank comprising a frame mounting means for conveying a blank, means for applying thermoplastic material to the upper face of said blank, a support pivoted to said frame in vertically spaced relation to the path of movement of said blank and means carried by said support for heating and spreading said thermoplastic material on said blank in uniform predetermined thickness, said last named means being vertically adjustable relative to said blank by pivoting of said support.
- 40 9. An apparatus for coating one face of a blank comprising a frame mounting means for conveying a coated blank, means for applying thermoplastic material to the upper face of said blank, and heated means for spreading said material uniformly in predetermined thickness on said blank including a support shiftable about a trans-
- 45 verse axis vertically spaced from the path of movement of said blank.
- 50 10. Coating apparatus comprising a conveyor for a rigid blank, means above said conveyor for flowing hot plastic on said blank, heated means in predetermined relation to said conveyor for re-heating and uniformly distributing said plastic on said blank, means adjacent said heated means for covering said reheated plastic with granular material, and heated means for guiding the movement of said coated blank on said conveyor. 55
- 55 11. Coating apparatus comprising a conveyor for a rigid blank, means for coating one face of said blank with thermoplastic material, and steam conduits parallel to said conveyor and engaged by the edges of said blank to guide the movement of said coated blank on said conveyor. 60
- 60 12. Apparatus for weatherproofing sheet building material comprising means for applying hot thermoplastic coating to one face of the material, means for smoothing out said coating, means for applying a layer of grit to said coating, suction means for removing loose excess grit thereon, a conveyor, and a heated guide for said material extending longitudinally of said conveyor and intermediate said coating and suction means for edge contact with the coated material. 65
- 65 13. Apparatus for weatherproofing rigid blanks comprising a conveyor, means for flowing thermoplastic coating on one face of said blank, and elongated heated members engaging opposite edges of said coated blank to guide said blank on said conveyor. 70
- 70 14. An apparatus for coating the upper face of a blank, comprising means for carrying a blank in horizontal position, including rotating feed rolls, means spaced from said rolls for flowing hot thermoplastic coating on the upper face of said blank, means for spreading said coating over said blank, and means above the blank and between said coating means and rolls for retaining excess coating piled up on said blanks by said spreading means spaced from said rolls. 75
- 75 15. An apparatus for coating one face of a rigid blank, comprising interrupted horizontal guide means for carrying a blank in horizontal position, means for flowing hot thermoplastic coating on the upper face of said blank, heated means for spreading said coating on said blank, and a pair of members at said interruption spaced in predetermined relation above and below said blank to control the thickness of the coating, the member engaging the uncoated face of the blank being heated. 80
- 80 16. The apparatus of claim 15, wherein said spreading means is carried by supporting means pivoted in vertically spaced relation below the blank. 85
- 85 17. The apparatus of claim 15, wherein said spreading means comprises vertically spaced rigidly interconnected steam pipes, one of said pipes below said blank being journaled in said blank carrying means. 90
- 90 18. The apparatus of claim 15, wherein the member engaging the coated face of the blank is eccentrically journaled in a support at its ends, and means for locking said member in predetermined position against rotation. 95
